HANDCART FOR MILK CANS AND THE LIKE

Roy E. Putman, Springfield, Mo.

Application March 4, 1947, Serial No. 732,168

4 Claims. (Cl. 214—65.4)

1

This invention relates to improvements in hand-carts and more particularly to a hand-cart designed for use in handling milk cans and the like.

An important object of the present invention is to provide a hand-cart of this character adapted to pick up one or more milk cans and to transport the cans from one place to another.

A further object of the invention is to provide a hand-cart of this character including a handle for manipulating the cart in a manner to engage and elevate a milk can or similar container and to lower the can upon the ground without the necessity of lifting the can into position on the cart or removing the can therefrom.

A further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view showing a can supported in position on the cart.

Figure 2 is a top plan view with the can removed therefrom.

Figure 3 is a side elevational view showing the cart in position for lifting the can or for discharging the can from the cart.

Figure 4 is a transverse sectional view taken substantially on a line 4—4 of Figure 2 and showing the cart tilted forwardly and supported on the prop, and

Figure 5 is an enlarged front elevational view of one of the swingable can supporting yokes.

Figure 6 is a front elevational view.

Referring now to the drawings in detail wherein for the purpose of illustration I have disclosed a preferred embodiment of the invention the numeral 5 designates a frame generally which comprises an inverted U-shaped frame member 6 and a second U-shaped frame member 7, the legs 8 of the frame member 7 being positioned inwardly of the legs 9 of the frame member 6 and in spaced parallel relation with respect thereto. The upper ends of the legs 8 are welded or otherwise suitably secured to the bight or top portion of the inverted frame member 6.

Rubber tired wheels 10 are positioned between the legs 8 and 9 of the respective frame mem-

bers and include axles 11 which are journaled in plates 12 welded or otherwise suitably secured to the rear edges of the respective legs.

A vertical brace 13 is positioned at the center of the top and bottom of the frame members 6 and 7 with the ends of the brace welded or otherwise suitably secured to said frame members.

Sleeves 14 are rotatably supported on the upper horizontal or bight portion of the frame member 6 at each side of the brace 13, the sleeves having arms 15 welded or otherwise suitably secured adjacent the ends of the sleeves and extending downwardly therefrom and with the lower ends of the arms welded to the sides of a horizontal yoke 16 which has its ends extended forwardly and curved outwardly as shown at 17.

A relatively larger yoke 18 is secured in a horizontal position under each of the yokes 16 by welding its ends to the center brace 13 and to one of the legs 8 of the frame member 7, the closed portion of both of the yokes extending rearwardly of said frame members.

A U-shaped handle 19 has its ends 20 bent downwardly and welded to the upper portion of the legs 8 of the inner frame member 7, the handle extending rearwardly of the frame and inclined slightly upwardly when the frame is positioned perpendicularly as shown in Figure 1.

A U-shaped bracket 21 is secured in a horizontal position to the upper portion of the brace 13 and is provided with a laterally extending pin 22 to which the upper end of a prop 23 is pivotally connected. The prop works between the sides of a U-shaped stop 24 which has its ends welded or otherwise suitably secured to the brace 13 below the bracket 21. The prop 23 is positioned rearwardly of the frame and its lower end swings outwardly in a rearward direction from the frame to engage the ground when the handle 19 is tilted downwardly to swing the lower end of the frame forwardly as shown in Figure 4 of the drawings whereby to support the cart in an inclined position, when not in use, and with the handle elevated above the ground.

In the operation of the device and when it is desired to lift a milk can 25 or the like onto the cart the handle 19 is tilted upwardly whereby to swing the frame members 6 and 7 rearwardly as shown in Figure 3 of the drawings, thus lowering the yoke 16 into a position for engaging the neck 26 of the can.

The handle 19 is then lowered to the position shown in Figure 1 which moves the wheels 10 forwardly and thus causes an upward movement of the yoke 16 to lift the can from the ground. The

pivotal suspension of the yoke 16 supports the can in a perpendicular position while the frames 6 and 7 swing forwardly to position the lower horizontal portion of inner frame 7 under the can and to position the lower yoke 18 behind the can to engage the lower portion of the can and to support the can in slightly rearwardly inclined position while the can is being transported by the cart.

The can is lowered and discharged from the cart by tilting the handle 19 upwardly and back-
ing the cart.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehend-
ed by the spirit of the invention as herein de-
scribed and the scope of the appended claims.

I claim:

1. A two-wheeled cart for containers of the class described and comprising an upright frame including vertical frame members and an upper horizontal frame member, wheels journaled on said vertical frame members, upper and lower yokes carried by said frame adapted to receive the upper and lower portions of a container for supporting the container in a suspended position on the frame, means swingably supporting the upper yoke on said horizontal frame member in a freely suspended horizontal position during tilt-
ing of the frame on the wheels and said lower yoke being rigidly connected in a horizontal position to the vertical frame members, and a handle extending substantially horizontally from the upper portion of said frame.

2. A two-wheeled cart for containers of the class described and comprising an upright frame including vertical frame members and an upper horizontal frame member, wheels journaled on said vertical frame members, a sleeve rotatable on the horizontal frame member, an upper yoke supported in a suspended horizontal position from said sleeve, a lower horizontal yoke rigidly connected to said vertical frame members, said yokes adapted to receive the upper and lower portions of a container for supporting the container in a suspended upright position on the frame, and a handle extending substantially horizontally from the upper portion of the frame and adapted to tilt the frame on the wheels to raise and lower a container engaged in said yokes.

3. A two-wheeled cart for containers of the class described and comprising an upright frame including vertical frame members and an upper horizontal frame member, wheels journaled on said vertical frame members, a sleeve rotatable on the horizontal frame member, an upper yoke sup-
ported in a suspended horizontal position from said sleeve, a lower horizontal yoke rigidly connected to said vertical frame members, said yokes adapted to receive the upper and lower portions of a container for supporting the container in a suspended upright position on the frame, a han-
dle extending substantially horizontally from the upper portion of the frame and adapted to tilt the frame on the wheels to raise and lower a container engaged in said yokes, and a prop pivoted to the upper portion of the frame for supporting the frame in a tilted position.

4. A two-wheeled cart for containers of the class described and comprising an upright frame including vertical frame members and an upper horizontal frame member, wheels journaled on said vertical frame members, a sleeve rotatable on the horizontal frame member, an upper yoke supported in a suspended horizontal position from said sleeve, a lower horizontal yoke rigidly connected to said vertical frame members, said yokes adapted to receive the upper and lower portions of a container for supporting the container in a suspended upright position on the frame, a handle extending substantially horizontally from the upper portion of the frame and adapted to tilt the frame on the wheels to raise and lower a container engaged in said yokes, and a prop pivoted to the upper portion of the frame for supporting the frame in a rearwardly tilted position.

ROY E. PUTMAN.
